1 Sheet Drawing. 13 Pages Specification

A plastic article such as a book back having a thinned portion acting as an elongated hinge which is caused to be tear resistant by ribs extending thereacross. The ribs are thicker than the thinned hinge portion and the molecular orientation of the material of the ribs is across the hinge line. Thus, the ribs provide an area in the hinge which is resistant to tearing along the line thereof and which confines any tearing which does occur to only a small portion of the hinge.
